UNITED STATES PATENT OFFICE.

ANTHONY E. WEINGARTNER, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

SIFTINGS PREVENTER FOR STOKERS.

Application filed January 21, 1924, Serial No. 637,534. Renewed June 22, 1928.

My invention relates to stokers, having particular relation to automatic stokers of the underfeed type.

One object of my invention is to provide 5 apparatus of the class described which includes a novel form of pusher, whereby the green coal may be progressively and positively moved from the retorts up over the tuyère plates.

10 In practice, the pusher mechanism is usually made and assembled without machined fittings in order to prevent the cost of the stoker equipment from becoming prohibitive. As a result, the more or less loose fit between 15 the pushers and the guides permits the escape of considerable quantities of the green coal as siftings. The accumulation of the siftings over a relatively short period of time is so great that it must be frequently 20 removed not only to avoid the clogging of the working stoker parts but also to avoid danger from fire.

Another object of my invention, therefore, 25 is to provide simple and inexpensive means for substantially avoiding the continued escape of the green coal between the relatively movable parts of the stoker mechanism.

A further object of my invention is to 30 provide pusher apparatus, wherein the siftings tending to work between the moving parts of the pusher constitute the sealing material, and wherein the efficacy of the seal thus formed increases with the length of service of the stoker.

35 With these and other objects and applications in mind, my invention further consists in the details of construction and operation and arrangement hereinafter described and claimed and illustrated in the accompanying drawings, wherein

Fig. 1 is a vertical, sectional view of the front portion of an inclined, underfeed stoker embodying my invention;

40 Fig. 2 is a perspective view of one of the pushers of Fig. 1;

Fig. 3 is a perspective view of one of the two sealing members which is designed to be detachably mounted on the structure of Fig. 2;

45 Fig. 4 is a similar view of an extension member for the structure of Fig. 2;

Fig. 5 is a similar view of one of the two sealing members designed to be detachably mounted on the structure of Fig. 4;

Fig. 6 is a side elevational view of the structures of Figs. 2 to 5, inclusive, in their assembled position;

Fig. 7 is a top-plan view of the structure of Fig. 6; and

Fig. 8 is a detail, transverse sectional view 60 taken on the line VIII—VIII of Fig. 1.

In the illustrated form of embodiment of my invention shown in Fig. 1 of the drawings, I provide an inclined, automatic stoker 1 of the underfeed type which has its upper 65 end carried by a front wall 2 and its lower end supported by a beam 3 of the main supporting frame. The stoker 1 may comprise a plurality of series of inclined tuyères 4, each series extending from a fuel supply opening 70 5 in the front wall 2 to a lower grate plate 6 which is supported on a movable structure carried by the main supporting beam 3.

A series of retorts 7, which respectively 75 alternate with the series of tuyères 4, are provided with a common inclined base section 8. The latter is slidably mounted on rails 9 and 11 carried by side tuyère supporting plates 12 and 13, respectively, all as will appear more fully hereinafter. The tuyère supporting plates 12 and 13 have their upper ends mounted upon the front wall 2 and their lower ends on the main beam 3. Each tuyère supporting plate may comprise two sections 80 14 and 15 which are secured together to form 85 a single supporting element, as shown in Fig. 1.

The stoker 1 may be supplied with material to be burned, say green coal, from a hopper 16 which opens into a cylinder 17 having an 90 operative connection with the inlet opening 5 in the front wall 2. The continuous passage of the green coal from the hopper 16 in through the furnace opening 5 and down into the retorts 7 may be effected by means 95 of a piston 18 which is slidably mounted in the cylinder 17. The piston 18 is operatively associated by means of a connecting rod 19 with a driving crank 20, which may be driven by power apparatus 21 of the usual type.

100 The inclined floor section 8 of each retort 7, which extends from the fuel inlet opening 5 to the grate plate 6, may be reciprocated by means of a pusher rod 22 which has an inner end secured to the movable floor 8 and an 105 outer end slidably mounted in a flanged head portion 23 of the cylinder 17. The outer end of the pusher rod 22 is provided with a

threaded boring 24 for the reception of a correspondingly threaded end portion of a rod 25 of reduced diameter with respect to the pusher rod 22. The piston 18 is provided with an extension 26 which is perforated to receive slidably the extension rod 25. On the outer end of the rod 25 is suitably mounted an adjustable stop 28.

When the piston extension 26 is reciprocated under the action of the crank 20 and connecting rod 19, the outer end of the pusher rod 22 and the adjustable stop 28 are successively engaged and moved an amount depending upon the position of the adjustable stop 28. Hence, it can be seen that while the piston 18 may have a stroke of, say, nine inches, the stop 28 may be so adjusted as to vary the stroke of the movable floor 8 from zero to that of said piston 18.

Referring more particularly to the construction of the movable floor 8, as shown in Figs. 2 to 8, inclusive, the same comprises a plurality of pushers 29 arranged in stepped relation, each pusher comprising a longitudinally extending member having substantially horizontal and inclined, front and rear top surfaces 31 and 32, respectively. Side surfaces 33 and 34 of each pusher are provided with grooves 35 and 36 adapted to receive slidably the guide rails 9 and 11, respectively, whereby the weight of each pusher may be individually supported upon its own guide rails.

Each pusher 29 is further provided with spaced recesses 37 and 38 (Fig. 6) opening into the base of the same, forming an intermediate wall 39 and a front end wall 40. In assembling the several pushers 29 to form the movable floor 8, the rear end of one pusher is mounted on the horizontal front surface 31 of the next pusher and the two are rigidly secured together by means of a plate 41 which is bolted to the end wall 40 of the lower pusher and to the intermediate wall 39 of the upper pusher.

A topmost pusher 42 is provided with an extension 43 (Fig. 4) having a top surface 44 and side surfaces 45 and 46, the latter being provided with grooves 47 and 48 continuous with the grooves 35 and 36, respectively. The extension 43 also has rear and front end surfaces 49 and 51, respectively, the former being secured to the front end wall 40 of the pusher 42 by means of bolts 52. The bolts 52 may also serve to secure a connecting member 53 to the front end surface 51 of the extension 43. The connecting member 53 is also rigidly secured to the inner end of the pusher rod 22.

As previously pointed out, experience has shown that as the several pushers 29 are moved back and forth intermediate the tuyère supporting plates 12 and 13, a considerable amount of the coal 54 (Fig. 8) being operated on sifts between said tuyère

supporting plates and said pushers and these sifts must be removed from time to time from under the stoker 1 in order to avoid the so-called "sealing up" of the stoker and the danger from fire. To this end, I provide a seal, wherein the escaping coal dust is the permanent filler.

The seal is formed by providing the upper corners 55 and 56 of each pusher 29 with longitudinally extending grooves 57 and 58, respectively, adapted to receive sealing member or liners 59 and 60. Each groove comprises an inclined wall 61 (Figs. 2 and 8) and a horizontal base portion 62. The several sealing members are loosely mounted in said grooved corners, the extent of lateral movement therein being determined by the walls 61 and the adjacent tuyère supporting plates 12 and 13. The lateral movement, however, is sufficient to permit a certain portion of the green coal 54 to work in between the side walls 61 and the adjacent sides of the sealing members 59 and 60, whereby a wedging action may obtain, wherein the opposite sides of the sealing members 59 and 60 are caused to engage frictionally the tuyère supporting plates 12 and 13. Such sifts as may work in between the sealing members 59 and 60 and the tuyère supporting plates 12 and 13, when the pushers 39 are first actuated, are not held in this position but falls through to the underside of the stoker 1. The material entering the space between the sealing members 59 and 60 and the walls 61, however, is caused to accumulate by reason of the horizontally extending base portions 62 of the corner recesses 55 and 56, wherein the sifts move in a horizontal direction as they tend to work between the moving parts. Experience has shown, however, that the accumulating sifts soon pack in this horizontal portion of the L-shaped seal, thereby preventing the further escape of the coal.

The sealing members 59 and 60 may be loosely locked in position by means of lugs 63 and 64 which are respectively secured to the rear and front portions thereof. Each rear lug 63 comprises a depending portion 65, which extends from the base of the sealing member, a laterally extending portion 66, which extends from the upper portion of the lug 63, and a longitudinally extending portion 67, which extends from the base portion of the depending portion 65. Each side of the pusher is provided with corresponding vertical, lateral and longitudinally extending recesses 68, 69 and 71, respectively, which are adapted to receive the lug portions just described.

The vertical lug portion 65 extending into the depending recess 68 avoids longitudinal movement of the liner. The longitudinally extending portion 67, extending into the adjacent recess 71, prevents vertical movement

beyond a predetermined extent. The lateral portion 66, extending into the recess 69 prevents the escape of siftings between the vertical locking portion 65 and the adjacent side wall of the recess 68. The lateral extension 66 also serves to avoid vertical movement of the sealing member beyond an extent sufficient to permit the siftings to work in between the base of the sealing member and the horizontal base portion 62. Lateral movement of the sealing member away from the wall 61 is limited by engagement with the adjacent tuyère supporting plate, as above set forth.

15 The front locking lug 64 is similar in design to the rear locking lug 63 with the exception that a longitudinally extending portion 72 thereof projects toward the rear end of the sealing member, whereas the corresponding extension 67 of the lug 65 extends toward the front end of said liner. The extension 43 is provided with sealing members 73 having locking lugs 74 and 75 at the opposite ends thereof as in the case of the sealing members 59 and 60. The construction of the extension 43 is otherwise as above indicated in the description of the pusher construction.

In operation, as coal is fed from the hopper 16 into the cylinder 17, the piston 18 operates to feed positively said coal through the stoker opening 5 down into the stoker retorts 7. The reciprocation of the piston 18 through the pusher rod 22 causes a limited reciprocation of the retort floor-structure 8, whereby 30 the green coal is gradually and continuously forced out of the retorts 7 up onto the tuyères 4, as will be readily understood by those skilled in the art.

The reciprocation of the several pushers 40 29, constituting the retort floor 8, causes a certain amount of the green coal to work in between the sealing members 59 and 60 and the adjacent walls 61 of the recessed corners 55 and 56. This sifting of material continues 45 until the coal has worked in between the base of the sealing members 59 and 60 and the horizontal portion 62 of the upper corner grooves where the sifting material tends to pack, thereby preventing the further escape 50 of siftings. Experience has shown that the seal thus formed becomes more effective as the pusher continues in service. As above noted, the sifting of the material between the adjacent vertical sides of the sealing members 59 and 60 and the pushers, operates 55 to force the liners into frictional engagement with the adjacent surfaces of the tuyère supporting plates, thereby preventing coal from sifting between these surfaces.

60 While I have shown only one embodiment of my invention, for the purpose of describing the same and illustrating its principles of construction and operation, it is apparent that various changes and modifications may 65 be made therein without departing from the

spirit and scope of my invention. I desire, therefore, that only such limitations shall be imposed thereon, as are indicated in the appended claims or as are demanded by the prior art.

70

I claim:

1. In a device of the class described, the combination with a pair of spaced supporting members provided with guide rails, of a pusher slidably mounted on said guide rails, the sides of said pusher adjacent to said members being provided with longitudinally extending recesses, and sealing members so loosely positioned in said recesses as to permit material to work in between said sealing members and said pusher to form a seal.

2. In a device of the class described, the combination with a pair of spaced supporting members provided with guide rails, of a pusher slidably mounted on said guide rails, the sides of said pusher adjacent to said members being provided with longitudinally extending recesses, and sealing members loosely mounted in said recesses, said sealing members being provided with locking lugs preventing longitudinal and vertical displacement beyond a predetermined extent.

3. In combination, a pusher having a top surface and grooved side surfaces, and a sealing member in each side groove provided with locking lugs preventing longitudinal and vertical displacement beyond a predetermined extent.

4. In combination, a pusher having a top surface, recessed side surfaces and grooved upper corners extending lengthwise of said pusher, and sealing members positioned in said grooved corners, said members being provided with locking lugs extending into the recesses in said side surfaces, whereby longitudinal and vertical displacement of said sealing members beyond a predetermined degree is prevented.

5. In combination, a pusher having a top surface, recessed side surfaces, and grooved upper corners extending lengthwise of said pusher, and sealing members positioned in said grooved corners, said members being provided with locking lugs extending into the recesses in said side surfaces, said locking lugs comprising vertical, lateral and longitudinally extending portions.

6. In combination, a pusher having a top surface, grooved upper corners extending lengthwise of said pusher and recessed side portions, each recess comprising a vertical portion extending from said groove, a lateral portion extending from said vertical portion and a longitudinal portion also extending from said vertical portion, and sealing members loosely positioned in said grooves said members having locking lugs so formed as to extend into said recesses.

7. In combination, a pusher having a top surface, grooved upper corners extending

130

- lengthwise of said pusher and recessed side portions, each recess comprising interconnected vertical, lateral and longitudinally extending portions, and sealing members 5 loosely positioned in said grooved corners, said members having locking lugs, each lug comprising vertical, lateral and longitudinally extending portions movable into said recesses.
10. 8. In combination, a pusher having a top surface and grooved side surfaces, sealing members loosely positioned in said grooves and provided with locking lugs, and a pair of spaced plates providing a slidable mounting for said pusher, the mounting of said members on said pusher being such that a part of the material to be operated on by said pusher works in between said members and pusher forming a seal, the members being forced into engagement with said plates by the wedging action of the sealing material.
9. In a device of the class described, spaced plates, a pusher slidably mounted on said spaced plates and provided with grooves extending lengthwise of said pusher, and siftings preventing means comprising sealing members positioned in said grooves and locked to said pusher, the members being movable into engagement with said plates as the material to be operated on works in between said members and said pusher.
10. 10. In a device of the class described, a pusher having a top surface, recessed side surfaces and grooves extending lengthwise of the pusher, spaced plates provided with rails extending into said recessed side surfaces, and sealing members loosely positioned in said grooves and locked to said pusher, the members being movable into engagement with said plates as the material to be operated on works in between said members and said pusher.
11. Stoker apparatus comprising a pusher, a pair of supporting members therefor, said pusher being provided with longitudinally extending recesses, and sealing members loosely mounted in said recesses, said sealing members being provided with locking lugs preventing longitudinal movement beyond a predetermined extent.
12. Stoker apparatus comprising a pusher having a detachable extension, corresponding sides of said pusher and extension being grooved, and sealing means positioned in said grooves and provided with locking lugs adapted to cooperate with said pusher and extension.
13. A pusher having a groove extending lengthwise thereof and also a recessed portion depending from said groove, and a sealing member loosely positioned in said groove and provided with a lug disposed in said recess, said lug tending to prevent the escape of siftings through said recess.
14. In a stoker, the combination with a pair of spaced supporting members, of a pusher slidably mounted thereon, the sides of said pusher adjacent to said members being provided with recesses, and sealing members loosely mounted in said recesses, said sealing members being provided with locking lugs preventing a vertical displacement beyond a predetermined extent.

ANTHONY E. WEINGARTNER.
